FLOOR MAT FOR AUTOMOBILES OR SIMILAR ARTICLE

Emanuel Meyer, 23 Latham Park, Melrose Park, Pa.

Filed July 25, 1962, Ser. No. 71,048

Term of patent 14 years

(Cl. D9—6)

FIG. 2 -**FIG. 3 -****FIG. 4 -****FIG. 5 -****FIG. 6 -****FIG. 7 -****FIG. 8 -****FIG. 10 -****FIG. 9 -**FIG. 1 is a top plan view of a floor mat for automobiles or similar article embodying my new design;

FIG. 2 is an enlarged fragmentary view of the portion of the mat enclosed within the broken line circle indicated by the reference II in FIG. 1;

FIG. 3 is an enlarged fragmentary view of the portion of the mat enclosed within the broken circle indicated by the reference III in FIG. 1;

FIG. 4 is an enlarged fragmentary sectional view taken along the lines and in the direction of the arrows IV-IV of FIG. 1, with portions broken away for convenience of illustration;

FIG. 5 is an enlarged fragmentary view of the portion of the mat enclosed within the broken line circle indicated by the reference V in FIG. 1;

FIG. 6 is an enlarged fragmentary view of the portion of the mat enclosed within the broken line circle indicated by the reference VI of FIG. 1;

FIG. 7 is a sectional view taken along the lines and in the direction of the arrows VII-VII in FIG. 5;

FIG. 8 is a sectional view taken along the lines and in the direction of the arrows VIII-VIII of FIG. 6;

FIG. 9 is an enlarged fragmentary sectional view taken along the lines and in the direction of the arrows IX-IX of FIG. 1;

FIG. 10 is an enlarged fragmentary view of the portion of the mat enclosed within the broken line circle indicated by the reference X of FIG. 1.

I claim:

The ornamental design for a floor mat for automobiles or similar article, as shown.
